UNITED STATES PATENT OFFICE.

HENRY Q. RUCKER, OF CLEVELAND, OHIO.

DESIGN FOR A TABLEWARE TRAY.

Application filed November 22, 1928. Serial No. 28,986. Term of patent 14 years.

To all whom it may concern:

Be it known that I, HENRY Q. RUCKER, a citizen of the United States, residing at Cleveland, in the county of Cuyahoga and State of Ohio, have invented a new, original, and ornamental Design for Tableware Trays, of which the following is a specification, reference being had to the accompanying drawing, forming part thereof.

In the drawings,

Figure 1 is a perspective view of a tableware tray, the view being taken from one end of the tray, and

I claim:

The ornamental design for a tableware tray, as shown.

HENRY Q. RUCKER.
